UNITED STATES PATENT OFFICE

WILLIAM B. FENN, OF SHEEPSHEAD BAY, NEW YORK.

CLOSURE DEVICE FOR JARS, BOTTLES, AND SIMILAR VESSELS.

No. 831,271.

Specification of Letters Patent.

Patented Sept. 18, 1906.

Application filed December 15, 1905. Serial No. 291,861.

To all whom it may concern:

Be it known that I, WILLIAM B. FENN, a citizen of the United States, residing at Sheepshead Bay, in the county of Queens and State of New York, have invented certain new and useful Improvements in Closure Devices for Jars, Bottles, and Similar Vessels, of which the following is a specification, such as will enable those skilled in the art to which it appertains to make and use the same.

This invention relates to closure devices for jars, bottles, and similar vessels, and particularly for vessels of this class made of glass or other earthenware; and the object of the invention is to provide a closure device for vessels of this class by means of which the said vessels may be securely closed and opened by hand whenever desired without the use of any instrument of any kind, a further object being to provide a closure device of the class specified which is particularly adapted for use in connection with fruit-jars and other jars designed for holding food products, but which may be employed in connection with vessels of the class specified designed for any purpose.

The invention is fully disclosed in the following specification, of which the accompanying drawings form a part, in which the separate parts of my improvement are designated by suitable reference characters in each of the views, and in which—

Figure 1 is a side view of the top portion of an ordinary jar provided with my improved closure device; Fig. 2, a similar view showing the closure device in section; Fig. 3, a vertical section on the line 3 3 of Fig. 2; Fig. 4, a horizontal section on the line 4 4 of Fig. 1; and Fig. 5, a partial section on the line 3 3 of Fig. 2, but showing a detail of the construction on an enlarged scale.

In the drawings forming part of this specification I have shown at *a* the top portion of an ordinary glass or similar jar, and said jar is provided with an enlarged and thickened neck *b*, the top portion of which is provided in the outer side thereof with a deep annular groove *b*¹, forming a reduced top neck portion *b*², having an inwardly-inclined outer wall *b*⁴, below which is an annular projecting ledge or shoulder *b*⁵, from the outer edge of which the wall of the bottom portion of the neck extends downwardly vertically, as shown at *b*⁶, to the bottom of the neck at *b*⁷.

Formed in the outer wall *b*⁶ of the neck, be-

low the annular groove *b*², are a plurality of downwardly-ranging annular grooves or recesses *c*, three of which are employed in the form of construction shown, and at the highest ends of these grooves or recesses the top edge of the annular projecting ledge *b*⁵ is beveled or rounded, as shown at *c*² in Fig. 5 and as is also shown in Fig. 2.

The closure device proper consists of a thin metal cap *d*, having a depending outwardly-inclined rim member *d*², the vertical width or depth of which is greater than the vertical width or depth of the top part *b*³ of the neck of the jar, and the rim member *d*² is provided at its bottom edge with an outwardly-directed flange *d*³, having a supplemental depending rim member *d*⁴, which is adapted to inclose and fit the bottom outer wall *b*⁶ of the neck of the jar, and said supplemental rim member *d*⁴ is provided centrally with inwardly-directed spring projections *d*⁵, which are triangular in form in vertical section and the bottom walls of which are inclined downwardly and outwardly, while the top walls thereof extend inwardly, as clearly shown in Fig. 5, and the number of these inwardly-directed spring projections *d*⁵ is equal to the number of the grooves or recesses *c*.

The supplemental rim member *d*⁴ at a predetermined point is divided vertically, as shown at *d*⁶, and one of the end portions of the rim *d*², formed by the division *d*⁶, is provided adjacent thereto with an aperture or hole *d*⁷, and said supplemental rim *d*⁴ is also preferably provided around its entire surface, except where the aperture or hole *d*⁷ and the inwardly-directed spring projections *d*⁵ are formed, with vertically-arranged teeth or projections *d*⁸, which give to said rim the appearance of milling. The central top of the cap *d* is preferably countersunk, as shown in Figs. 2, 3, and 4, and the rim member *d*² thereof is provided with annularly-arranged inwardly-directed projections *e*, which are stamped therein, as hereinafter described.

Within the rim portion *d*² of the cap *d* is placed an annular packing band or gasket *f*, composed of fiber or similar material saturated with paraffin or a suitable composition which will preserve said band or gasket and render it impervious to all kinds of liquids and gases, and the vertical width or depth of said band or gasket is slightly greater than the vertical width or depth of the outer wall *b*⁴ of the top neck portion *b*³ of the jar, and the top edge of said band or gasket *f* is

in the form of construction shown beveled outwardly, as shown at f^2 , and placed in the top portion of the cap d and resting on the top wall of the part b^3 of the neck of the jar is a 5 packing-disk f^3 , composed of the same material as the packing band or gasket f , and the outer edge of which is beveled to fit the bevel at f^2 of said band or gasket f , and the perimeter of the central portion of the cap 10 d or the outer edge thereof is provided with a raised annular portion g , which forms a corresponding groove within said cap and around the central depressed portion d thereof and in which the outer upper edge of the 15 band or gasket f and the disk f^3 fit, as clearly shown in Fig. 5. The bevel arrangement of the annular packing band or gasket f and the packing-disk f^3 at f^2 is, however, not an essential feature of this construction, and the 20 disk f^3 may rest on the band or gasket f , and when the parts are pressed together and secured in the cap d they assume substantially the form and position shown in Fig. 5.

The backing band or gasket f and the 25 packing-disk f^3 are secured in the cap d before said cap is placed on the jar, and in this operation the said cap and packing band or gasket f and packing-disk f^3 are connected by pressure applied thereto in a suitable 30 press, and in this operation the inwardly-directed projections e of the rim member d^4 are also formed and forced into the packing band or gasket f , and in this way the parts f and f^3 are permanently secured in the cap d .

35 The supplemental depending rim member d^4 of the cap d is provided at or near the top thereof with a deep annular score-line h , whereby the supplemental rim member d^4 may be torn off in the operation of opening 40 the jar, as hereinafter described.

In closing a jar made in the manner described with my improved closure device the cap d is grasped in one hand and is forced down onto the neck of the jar, and in this 45 operation the cap is held so that the inwardly-directed spring projections d^5 of the supplemental rim member d^4 will pass downwardly over the beveled portions c^2 of the ledge d^5 into the annularly-arranged grooves or recesses c , and the cap is then turned to the right, and in this operation the said inwardly-directed projections d^5 operate on the top 50 inclined walls of the recesses or grooves c so as to securely lock the cap to the jar, and in this operation the packing band or gasket f and the packing-disk f^3 are securely pressed into their proper positions on the neck of the jar. In opening the jar one end of the supplemental rim member d^4 is grasped at the 55 vertical division d^6 of said rim and said rim is pulled off or detached from the rest of the cap. The aperture or hole d^7 in the rim member d^4 is intended to permit of the insertion of a suitable device in order to raise the end of the rim and permit it to be grasped

by the fingers; but said aperture or hole d^7 is not absolutely essential.

In my improvement the packing-disk f^3 is not absolutely essential under all conditions or in all of the uses to which my improved closure device may be applied, and said packing-disk f^3 may in some cases be omitted. After the supplemental rim member d^4 has been torn off as above described the cap may be lifted from the jar, and said cap may be used to close the jar after the same has been partially or entirely emptied, if desired, that part thereof above the supplemental rim member d^4 serving for this purpose.

It will be understood that the cap d is composed of thin flexible metal and the supplemental rim member d^4 thereof is formed in such manner as to possess suitable elasticity and will yield without being forced out of shape or destroyed in the operation of pressing the cap onto the jar and locking it thereto.

Although I have shown and described the use of my improved closure device in connection with a jar only, it will be apparent that the same may be applied to bottles, jugs, and other vessels of this class.

Having fully described my invention, what I claim as new, and desire to secure by Letters Patent, is—

1. A jar or other vessel provided with a top neck portion and a cap provided with a depending rim adapted to engage said top neck portion, and an annular packing band or gasket secured in said rim and adapted to inclose and fit the top neck portion of the vessel, said cap being also provided with a packing-disk adapted to rest on the top neck portion of the vessel, and the outer edge of which is beveled to fit a corresponding bevel on said band or gasket, substantially as shown and described.

2. A closure device for jars and other vessels, provided with a depending rim member adapted to fit a corresponding part of the neck of the vessel and to inclose the same, said corresponding part of the neck of the vessel being provided at intervals with annularly-arranged grooves or recesses all of which are inclined downwardly in the same direction, said rim member being provided with inwardly-directed spring projections adapted to enter said recesses, said rim being detachable in the operation of opening the vessel, substantially as shown and described.

3. A jar or similar vessel, the neck of which is provided near the top thereof with a deep annular groove forming a top neck portion at the base of which is an annular ledge or projection, the edge of which is beveled or rounded at intervals, the annular base portion of the neck below said beveled or rounded portion of said ledge or projection being provided with annularly-arranged grooves or recesses, and a cap provided with a depending

rim member adapted to inclose the top neck portion, an annular flange adapted to rest on said annular ledge or projection, and a supplemental rim portion adapted to inclose the base portion of the neck, said supplemental rim member being provided with inwardly-directed projections, and being also adapted to be torn off in the operation of opening the vessel, substantially as shown and described. —————— and the neck of which supplemental rim portion adapted to inclose the base portion of the neck, said supplemental rim member being provided with inwardly-directed projections, and being also adapted to be torn off in the operation of opening the vessel, and the first-named depending rim member of the cap being also provided with an annular packing band or gasket which is secured therein and adapted to fit the outer wall of the top neck portion, and said cap being also provided with a

4. A jar or similar vessel, the neck of which is provided near the top thereof with a deep annular groove forming a top neck portion at the base of which is an annular ledge or protuberance, and said cap being also provided with a packing-disk which is adapted to rest on said top neck portion, substantially as shown and described. 60

25 the base portion of the hook, and the inner rim member being provided with inwardly-directed projections, and being also adapted to be torn off in the operation of opening the vessel, and the first-named depending rim member of the cap being also provided with an annular packing band or gasket which is secured therein and adapted to fit the outer wall of the top neck portion, substantially as shown and described.

30

7. A closure-cap for jars and other vessels provided with an inner packing-disk adapted to rest on the neck of the vessel, a depending annular rim having an inner annular packing-gasket adapted to inclose the top portion of the neck of the vessel, and a supplemental depending member connected with said rim, means whereby the supplemental depending member may be locked to the neck of the vessel, substantially as shown and described.

35 substantially as shown. 5. A jar or similar vessel, the neck of which is provided near the top thereof with a deep annular groove forming a top neck portion at the base of which is an annular ledge or projection, the edge of which is beveled or round- member may be locked to the neck of the vessel, and said supplemental depending member being detachable from the cap in the operation of opening the vessel, substantially as shown and described. 85

45 vided with annularly-arranged grooves or recesses, and a cap provided with a depending rim member adapted to inclose the top neck portion, an annular flange adapted to rest on said annular ledge or projection, and a
